[57] CLAIM

The ornamental design for a saw handle, as shown and described.

DESCRIPTION

FIG. 1 is a right-side view of a saw handle showing my new design;

FIG. 2 is a bottom view thereof;

FIG. 3 is a top view thereof;

FIG. 4 is a left-side view thereof;

FIG. 5 is a front view thereof; and,

FIG. 6 is a back view thereof.

The broken line showing of FIG. 1 is for illustrative purposes only and forms no part of the claimed design.
